UNITED STATES PATENT OFFICE.

MAGULER BUTLER, OF ROCHESTER, NEW YORK.

DESIGN FOR A BICYCLE-HOLDER.

SPECIFICATION forming part of Design No. 28,228, dated February 1, 1898.

Application filed December 3, 1896. Serial No. 614,367. Term of patent 3½ years.

To all whom it may concern:

Be it known that I, MAGULER BUTLER, a citizen of the United States, and a resident of the city of Rochester, county of Monroe, and State of New York, have invented and produced a new and original Design for Bicycle-Holders, of which the following is a specification, reference being had to the accompanying drawings, in which—

Figure 1 is a perspective view of one of my holders, and Figs. 2 and 3 are respectively top plan and end views of one of the wire-holders thereof.

The leading features of my design are the general form and appearance thereof and the form and appearance of the wire holder thereof.

A is the back plate, having the rounded ends *a* bent at right angles to the main portion *b* of the back plate, and between the two ends and upon each end *a* is a wire holder *B*, having a main portion *b*, substantially of T shape, as shown in Fig. 2, and having curved por-

tions *b'* *b'* on the ends of the cross-bar of the T, and having also a curved portion *b*² on the remaining leg of the T. On the main portion *b* of each arm holder *B* is a cylindrical projection *b*³, which passes through a perforation in the end *a* and bears outside of an end *a* a polygonal piece *b*⁴. Through the curved portions *b'* and *b*² and from one of the T-formed pieces *B* to the other extends a rod-formed portion *C*, which has a substantially semicircular curve through and around the curved ends *b* *b*², the two rod-like portions 30 being parallel and having each a looped portion *C'* connected by the inwardly-curved portion *c'*.

What I claim is—

The design for a bicycle-holder, substantially as herein shown and described.

MAGULER BUTLER.
